UNITED STATES PATENT OFFICE.

HERBERT W. SELLNER, OF FARIBAULT, MINNESOTA.

FOLDING TABLE.

1,235,934.

Specification of Letters Patent.

Patented Aug. 7, 1917.

Application filed June 22, 1916. Serial No. 105,268.

To all whom it may concern:

Be it known that I, HERBERT W. SELLNER, a citizen of the United States, residing at Faribault, in the county of Rice and State 5 of Minnesota, have invented certain new and useful Improvements in Folding Tables; and I do declare the following to be a full, clear, and exact description of the invention, such as will enable others skilled in the art 10 to which it appertains to make and use the same.

This invention relates to new and useful improvements in tables, and more particularly to tables which are adapted to be folded, and the primary object of the invention 15 is to provide a folding table which has swinging leaves, and said leaves being provided with means for automatically bringing a support for the same to operative position 20 when they are raised.

Another object of this invention is to provide a folding table of the pedestal type, which has a central square upright comprised of four standards and a top having 25 a pair of swinging leaves, two of the standards being pivoted and carrying leaf supporting arms, which are adapted to automatically swing into position beneath the leaves when they are raised.

30 A further object of the invention is to provide a device of this character which is easily and simply constructed, inexpensive to manufacture, and one which will be very efficient in operation.

35 With these and numerous other objects in view, my invention consists of the novel features of construction, combination and arrangement of parts which will be herein referred to and more particularly pointed 40 out in the specification and claim.

In the accompanying drawings:

Figure 1 is a side elevation of the table in open position;

45 Fig. 2 is a similar view taken at right angles to Fig. 1;

Fig. 3 is a side elevation showing the table in closed position;

Fig. 4 is a horizontal section taken on the line 4—4 of Fig. 1;

50 Fig. 5 is a horizontal section taken on the line 5—5 of Fig. 1; and

Fig. 6 is a horizontal section on the line 6—6 of Fig. 3.

In describing my invention, I shall refer 55 to the drawings in which similar reference characters designate corresponding parts

throughout the several views and in which my folding table, which is of the pedestal type, is shown having a top 1 with a central square upright 2, which connects the top 60 with a base 3. The top 1 comprises a central stationary portion 4, having hinged to opposite sides of the same a pair of leaves 5. This top 1 may be of any desired shape, either square or rectangular as preferred. The 65 hinges 6 that secure the leaves 5 to the standard portion of the table, are secured to the lower surface of these parts as clearly shown in Fig. 4 of the drawings.

Secured to the lower surface of the central portion 4 of the top, and centrally positioned with respect thereto is a plate 7, to the lower surface of which is connected the upper end of the centrally disposed upright 2. This plate 7 is positioned directly above 75 the base 3 of the table, and the square upright 2 forms a connection between these two parts.

The upright 2 comprises four substantially rectangular-shaped standards, two diagonally positioned standards which are designated by the numeral 8 being stationary, while the correspondingly positioned standards 9 are pivotally mounted between the base and plate. These standards 8 and 9 are 80 all substantially rectangular shaped, and are so closely positioned, that they will form a substantially square upright support for a table.

Projecting laterally from opposite sides of 90 the upper ends of the pivoted standards 9 are arms 10, which are adapted to form leaf supports when they are in position. These arms when not in position to hold the leaves 5, are adapted, owing to the fact that the 95 standards 9 can rotate, to swing beneath the stationary portion 4 of the table top. The movement of the arms 10 is limited by stops 11 and 12 positioned respectively on the lower surface of the leaves 5, and the stationary portion of the table top.

Connecting the arms 10, and the leaves 5 are coil springs 13, which have one of their ends 14 secured to the lower surface of the swinging leaves and points adjacent the 105 edges of the same, while the opposite ends 15 of these springs are secured to the opposite sides of the said arms. From this arrangement when the swinging leaves 5 are lowered, the arms 10 on the pivoted standards 110 will be positioned beneath the stationary portion of the table top, but when the swing-

ing leaves of the table are raised, a constant outward pull will be exerted on the leaf supporting arms 10 and when the leaves are level with the stationary top of the table, the 5 arms 10 will automatically swing outwardly until their movements are checked by the stops 12. This will bring the arms 10 to operative position and will support the swinging leaves.

19 Projecting from the lower ends of the standards 8 and 9 are supporting feet 16, which have downwardly projecting lower ends 17 disposed in a single plane with the lower surface of the base 3. By this means 15 the table will be securely supported in various positions. When not in use the legs or feet on the pivoted standards 9 will be swung adjacent the feet on the stationary standards owing to the swinging movement 20 of the leaf supporting arms 10 on the upper ends of the pivoted standards. In this position, the table is folded and will occupy a small amount of space. When the table is unfolded, the leaf supporting arms will 25 swing outwardly, and consequently the feet 16 of the same will swing in the same direction to the position shown in Figs. 1 and 2 of the drawings whereby the table will be securely supported by the feet projecting 30 from the central support from four sides.

From the foregoing description of the construction and operation of my folding table, it will be obvious that I have provided a simple and efficient device for carrying out 35 the objects of this invention. Attention is particularly called to the automatic arrangement whereby when the leaves of the table are swung to operative position, the horizontally swinging leaf supporting arms

on the pivoted standards will immediately 40 be positioned beneath the leaves to support the same. This automatic positioning is brought about by the coil springs that connect the arms with the lower surface of the leaves. It will be noted that the leaf supporting arms will not swing outwardly until the leaves are in position, but they will be under a constant outward pull owing to the expansion of the coil connecting springs. The movement of these arms 10 is limited by 45 stop members on the lower surface of the leaves and stationary portion of the top 1.

I claim:

A pedestal table comprising a stationary top, a plate secured to the lower surface of the same, a base positioned beneath said plate, four substantially rectangular shaped standards connecting said plate and base and closely positioned to form a square upright, two diagonally positioned standards being stationary, and the remaining two being pivotally mounted between the base and plate, laterally projecting arms on the opposite outer sides of the pivoted standards, laterally projecting supporting feet on the lower ends of said standards, swinging leaves on opposite sides of said top, coil springs connecting said arms and leaves, and stops on the lower surface of the leaves and top to limit the movements of said arms. 55 60 65 70

In testimony whereof I have hereunto set my hand in the presence of two subscribing witnesses.

HERBERT W. SELLNER.
